E. E. BRADLEY,
SPINNING MACHINE,
APPLICATION FILED JAN. 25, 1919.

1,425,363.

Patented Aug. 8, 1922.

UNITED STATES PATENT OFFICE.

EDWARD E. BRADLEY, OF STONINGTON, CONNECTICUT, ASSIGNOR TO THE ATWOOD MACHINE COMPANY, OF STONINGTON, CONNECTICUT, A CORPORATION OF NEW JERSEY.

SPINNING MACHINE.

1,425,363.

Specification of Letters Patent Patented Aug. 8, 1922.

Application filed January 25, 1919. Serial No. 273,088.

To all whom it may concern:

Be it known that I, EDWARD E. BRADLEY, a citizen of the United States, and resident of Stonington, in the county of New London and State of Connecticut, have invented a new and useful Improvement in Spinning Machines, of which the following is a specification.

This invention relates to improvements in spinning machines with the object in view of providing a machine having a plurality of individual electric motor driven spindles and a separate electric motor driven take up mechanism, the motors for the spindles and the motor for the take up mechanism being synchronized.

A practical embodiment of my invention is represented in the accompanying drawings in which,

20 Fig. 1, represents a front elevation of one end of a spinning machine with the electric motor for driving the take up feed rolls applied thereto, and the electric motor driven spindles in position thereon, and

25 Fig. 2, represents an end elevation of the same, one of said spindles being shown in section.

The main frame, of which one vertical standard is shown, is denoted by 1, the spindle rails supported thereon by 2, the take up spools by 3 and their driving drums by 4. The shafts 5 of the driving drums are journaled in the frame 1, and geared together by gears 5*. One of the shafts 5 is

30 provided with a driving gear 6 which receives its motion from an electric motor 7 through a worm 8 on the shaft 9 of the motor, which worm meshes with a wormwheel 10 having a gear 11 formed integral there-

35 with and loosely mounted on a stud 12 fixed on the frame. An intermediate gear 13 is adjustably mounted on a bracket 14 carried by the frame and meshes with the gear 11 and the gear 6. The motor 7 is carried

40 by a bracket 15 extending laterally from the frame 1.

Each spindle comprises the step 16 flexibly mounted on the spindle rail 2 and the blade 17 rotatably mounted in the step.

45 50 In the embodiment which I have illustrated in the accompanying drawings, the step comprises a ring portion 18 which forms a housing for the field 19 of the electric motor, and centrally arranged upwardly

55 and downwardly projecting portions 20—21

for receiving the blade 17 of the spindle. The blade 17 is provided with a hollow downwardly directed shield 22 which surrounds the upwardly projecting portion 20 of the step, and which carries an armature 23 and commutator ring 24 of the electric motor. The commutator bushes 25 are carried by the ring portion 18 of the step.

The spindle rail 2 has a hole 26 through which the portion 21 of the step projects. 60 Cushion washers 27 and 28 are provided at the top and bottom of the hole 26 surrounding the portion 21. A coil spring 29 is located between the washer 28 and a nut 29* which is screwed onto the end of the 65 portion 21.

The main circuit cable is denoted by 30, and the cables to the spindle driving motors by 31 and the cable to the take up roll driving motor by 32.

70 The electric motors for all of the spindles are connected in series and synchronized so that the spindles may be driven at the same speed; any well known or approved means for accomplishing this result being utilized.

75 The take up roll driving motor 7 is synchronized with the spindle driving motors, but the motor 7 will, of course, be driven at a much slower speed than the spindle driving motors to ensure the proper twist to the thread passing from the spindles to the take up rolls.

80 The electric motor driven spindle mechanism shown and described but not specifically claimed herein, is the subject matter of my co-pending application for patent Serial No. 266322 filed December 11, 1918.

85 While I have shown my invention in connection with a take up feed roll mechanism it is obvious my invention could be equally well applied to a delivery feed roll mechanism.

90 95 What I claim is:

In a spinning machine, individual electric motor driven spindles, means coaxing with said spindles for self balancing them, and electric motor driven feed rolls, the motors for the spindles and feed rolls being synchronized.

100 105 In testimony, that I claim the foregoing as my invention, I have signed my name, this 24th day of January 1919.

EDWARD E. BRADLEY.
